 Calif., a corporation of Delaware

Application August 2, 1940, Serial No. 349,417

4 Claims. (Cl. 159—27)

This invention relates generally to apparatus and methods for the concentration of various liquid materials by evaporation.

It is an object of the invention to provide an improved evaporating apparatus and method applicable to a wide variety of materials, including materials containing substantial amounts of solids in suspension such as tomato pulp, as well as materials such as milk products.

Another object of the invention is to provide evaporating apparatus capable of concentrating materials like tomato pulp to paste-like consistency, without causing undue retention or accumulations of the material in different parts of the equipment.

A further object of the invention is to eliminate or minimize clogging or incrustation of evaporating tubes, such as is troublesome in conventional equipment when certain types of materials are handled.

Another object of the invention is to provide evaporating apparatus which will afford utmost capacity for a given size of equipment and for a given number of evaporating tubes.

Further objects of the invention will appear from the following description in which the preferred embodiments of the invention have been set forth in detail in conjunction with the accompanying drawings.

Referring to the drawings:

Fig. 1 is a side elevational view, diagrammatically illustrating evaporating apparatus incorporating the present invention;

Fig. 2 is an enlarged detail, partly in cross section, illustrating the upper portion of the first evaporating unit;

Fig. 3 is an enlarged side elevational detail, illustrating the upper portion of the left hand unit of Fig. 1; and

Fig. 4 is an enlarged cross sectional detail showing a possible modified form of distributing or plenum chamber.

Although the present invention can be incorporated in a single effect evaporator, the drawings illustrate equipment incorporating two units A and B. As will be presently explained, each unit utilizes two sets of evaporating tubes which are disposed within a common heating jacket.

Referring first to the construction of the first unit A, it consists of a heating jacket 10 which surrounds the two groups of upright evaporating tubes 11 and 12. The upper and lower ends of these tubes are secured to the tube sheets 13 and 14. The heater jacket is provided with a portion 15 at its upper end which accommodates for un-

equal expansion or contraction. The tubes 11 are grouped about the longitudinal axis of the jacket 10 and occupy a substantially cylindrical space. The tubes 12 are disposed in an annular space about the group 11. Disposed below the lower tube sheet 14 there is a liquid inlet chamber 16, whereby liquid material can be introduced into the lower ends of tubes 11. The lower ends of the tubes 12 discharge into the collecting and separating chamber 17.

Mounted upon the upper tube sheet 13, there is a plenum chamber 18 which serves to establish communication between the upper ends of the two sets of tubes. According to the details of Fig. 2, the chamber 18 is cylindrical and of adequate diameter for positioning over the tubes. The lower end of the plenum chamber is shown removably clamped by bolts 19 to the short extension neck 21, which in turn is clamped upon the upper side of the tube sheet 13. It will be noted that the chamber is relatively high compared to its diameter.

Within the chamber 18 there is a deflector means 22 which serves to maintain a liquid-free vapor space 23 in the upper part of the chamber. This deflector means in this instance consists of a tapered nozzle 24 in conjunction with a semi-toroidal deflector 25. The nozzle 24 has its lower end supported by spaced pins 26, which in turn rest upon the tube sheets 13. The lower part of the nozzle is also provided with an inner spider 27 which is secured by stud 28 to the central part of the tube sheet. The diameter of the lower end of the deflector nozzle is such that it receives the discharge jetting from the upper end of the tubes 11, without obstructing downflow of material into the upper ends of the outer group of tubes 12.

The upper and smaller end of the nozzles 24 discharges directly against the under side of the deflector 25. The deflector 25 is shown carried by stud 31, which in turn is secured to a spider 32 fixed within the upper end of nozzle 24.

A connection is provided to the upper end of chamber 18 for venting a portion of the vapor from space 23. Thus, an outlet fitting 33 is shown mounted upon the upper end of chamber 18, and this fitting is arranged to accommodate a flow control orifice plate 34. Pipe 36 connects to the fitting 33.

Suitable vapor and liquid connections for the first unit A are shown in Fig. 1. Line 37 represents introduction of steam into jacket 10, and lines 38 and 39 are for removal of non-condensables and condensate respectively. Line 41 represents the liquid flow to the effect A, and con-

nects with the liquid chamber 18. Line 42 connects to the lower end of the collecting chamber 17 and serves to remove the concentrated liquid material. Line 43 represents removal of vapor from the chamber 17. This line connects to suitable condensing means as will be presently explained.

Operation of the evaporating unit described above can be outlined as follows: The liquid to be evaporated is preheated by means to be presently explained and is then delivered to the first unit A through line 41. Assuming proper heating of the evaporating tubes by steam introduced into the heating jacket 10, the liquid pumped through line 41 flows into the lower end of the inner group of tubes. Evolution of vapor occurs due to heat absorption through the walls of the evaporating tubes, and as a result vapor, together with dispersed liquid material, flows upwardly at high velocities through the tubes 11, to be discharged in the form of jets from the upper ends of these tubes. Nozzle 24 directs this discharge against the upper side of the deflector 25, by means of which the flow is directed generally downwardly around the nozzle 24 and toward the upper ends of tubes 12. Some vapor finds its way upwardly into the space 23, from which vapor is continuously withdrawn through the orifice plate 34 and pipe 36. The material entering the upper ends of the downflow tubes 12 consists of droplets of the liquid material dispersed in the vapor, thus making for good distribution to the several tubes 12. In other words, there is no collection of liquid material as a pool upon the tube sheet 13, with the liquid from this pool running into the upper ends of the pipes 12. Formation of such a liquid pool is highly objectionable, in that it tends to give poor distribution of liquid into the several tubes, with uneven streams of liquid material, rather than even films upon the inner surfaces of the tubes. The annular gap 29 at the lower end of the nozzle enables passage of any collected liquid material.

It is possible to operate the apparatus described above without withdrawal of vapor through pipe 36. However, by withdrawing a certain amount of vapor through this pipe, and from the vapor space 23, it is possible to decrease the amount of vapor entering the tubes 12. Such bleed-off of vapor makes it possible to so operate the apparatus that the amount of vapor entering the tubes 12 bears such a ratio to the amount of liquid carried by the vapor, that optimum evaporating conditions may take place within the tubes, without clogging or incrustation. Without such a bleed-off, there would be too much vapor in proportion to the liquid material in the mixture entering tubes 12 to make for favorable evaporating conditions within these tubes, even though one might attempt to accommodate such an increased amount of vapor by utilizing a larger number of the tubes. It may be explained in this connection that if the velocity of vapor flowing through the evaporating tubes becomes too high, the filming of the inner walls of the tube is not proper for optimum operation, and incrustation and clogging results, particularly when evaporating certain viscous materials such as pulps or pastes. This is attributed to a breaking or tearing away of films or causing the film to become so excessively thin on the inner surfaces of the tubes by the extremely high velocities that the resulting very high rate of heat transfer actually dries or so concentrates the liquid that incrustation results. For example if it were at-

tempted to secure concentration of tomato pulp by treatment in a single evaporating tube twice the length of tubes 11 and 12, the velocity would become too high and as a result the inner surface of the tube would accumulate an incrustation of solid material, particularly near the discharge end of the tube where the velocities are greatest. With the present apparatus the downflow tubes 12 would be subject to heavy incrustation and even finally to clogging if no vapor is withdrawn from chamber 23, and the deposit so formed would be more prevalent toward the discharge end of the tubes.

To prevent this, the mount of vapor which should be bled off from chamber 18 in proportion to the amount of vapor discharged from the tubes 11, to secure good results, will depend upon various factors, including the concentration being obtained, the amount of water being removed from a given amount of feed material, the ratio between the cross sectional flow area afforded by the upflow and downflow tubes, the ratio between the cross sectional area of each tube and its inner circumference, and the properties of the material being handled. In practice, where a suitable bleed-off orifice has not been previously determined for a given installation, a hand throttling valve is inserted in line 36 and the fixed orifice plate removed. The hand valve is then adjusted until when operating at desired capacity, incrustation or clogging does not take place or is reduced to a minimum, and optimum operation is secured. Thereafter an equivalent fixed orifice can be substituted for the throttling valve. In a number of installations for the evaporation of tomato pulp, where the pulp is being concentrated from 6% to 14% solids in unit A, and where the tubes are 1½ inches inside diameter and about 20 feet long, with thirty four of tubes 11, and twenty seven of tubes 12, good results are secured by diverting about 25% of the vapor discharged into chamber 18 from the upflow tubes 11. In other instances, under different conditions of design and operation, the amount of vapor diverted for best results may vary over a substantial range, as for example from 10 to 70%.

The deflector 25 serves the purpose of providing a space 23 above this deflector, which is relatively free of entrained liquid and from which vapor alone can be withdrawn through pipe 36.

The second unit B is similar in some respects to the unit A, but it does not make use of an entrainment separator, and it is not provided with a bleed-off for vapor from the upper plenum chamber. Briefly, the unit B includes the heater jacket 44, which surrounds the upflow tubes 46 and the downflow tubes 47. The ends of these tubes connect with the upper and lower tube plates 48 and 49. The plenum chamber 51, mounted upon the tube plate 48, is similar to the chamber 18 for the effect A, except that in the embodiment of Fig. 3 its interior is unobstructed. The lower end of downflow tubes discharge into the collecting chamber 52, and liquid collected in this chamber is removed through pipe 53, and vapor through conduit 54. Line 56 represents introduction of heating steam to jacket 44. Lines 57 and 58 represent, respectively, removal of non-condensables and condensate. Liquid in the chamber 59 communicates with the lower ends of the upflow tubes, and this chamber is shown being supplied with material from the first unit A, through pipe 42 and pump 61.

As auxiliary equipment which can be used with

the two units A and B, one can employ a pre-heater 62 for heating liquid being supplied to the first effect A. This heater can be of the closed tube type, with the tubes being heated by vapor from conduits 43 and 44. Vapor discharged from the preheater by line 63 is shown merging with the vapor being vented through pipe 36 of the first effect. Pump 64 is shown delivering liquid to be concentrated to the preheater 62, while the heated liquid leaving the heater flows through pipe line 41, to the first effect.

The second unit B operates in substantially the same manner as the first effect A insofar as flow of material through the evaporating tubes is concerned. It is unnecessary in this instance to bleed off vapor from the chamber, because the material being handled is relatively concentrated and the amount of vapor evolved is insufficient to cause detrimental effects such as described in connection with unit A.

The use of a relatively high plenum chamber 51 serves to prevent plastering of the top wall of this chamber with liquid material being concentrated. This can be better understood when it is considered that the material jetting from the upper ends of the upflow tubes 46 consists of liquid, solids suspended in the same, and vapor, or in other words liquid material dispersed as small droplets in the vapor. Droplets of liquid material leaving the upflow tubes are propelled upwardly at considerable velocity, and if these droplets are permitted to impact the top wall of the plenum chamber, they serve to plaster this wall instead of remaining in entrainment with the vapor. When such plastering occurs large masses of the material accumulate and occasionally slough off thus overloading some of the tubes. Such plastering is particularly detrimental to operation of the apparatus, because it causes a certain amount of the material undergoing concentration to be subjected to the treatment temperatures for unduly long periods of time, and in addition it makes for poor redistribution of the liquid material in the downflow tubes 47. It will be evident that material sloughing off or streaming down the inner side walls of the plenum chamber 51 will not be re-distributed as droplets in the vapor entering the downflow tubes 47, but will flow as uneven streams of liquid material into the downflow tubes.

With a plenum chamber of sufficient height, as for example of the order of 3½ feet high for tubes 1¼ inch inside diameter and about 20 feet long, the liquid material projected upwardly from the upper ends of the upflow tubes loses its upward velocity component before reaching the top wall of the plenum chamber, and thus the majority of the liquid masses or droplets do not contact the walls of the plenum chamber before being reintroduced together with vapor into the downflow tubes 47. The minimum height required will vary in different instances, since it depends upon various factors including the amount of solids in the liquid material, the weight of the solids, the viscosity of the material and the velocity, with which vapor is discharged from the upflow tubes.

In addition to the type of plenum chamber shown in Fig. 3, it is possible to utilize a chamber of lesser height in conjunction with means for checking and diffusing the material jetting from the upflow tubes 46. Such an arrangement is shown in Fig. 4. The plenum chamber 66 in this instance is relatively short compared to the height of chamber 51 in Fig. 3, and within the plenum chamber there are a plurality of screens

67 which are carried by the removable ring 68. These screens extend across the upper ends of the evaporating tubes, and they are impacted by the vapor and liquid material jetting from the upflow tubes. Because of the checking and diffusing-action of the screens 67, the upward velocity component of particles of liquid material issuing from the upflow tubes is reduced before such particles can impact the top wall of the plenum chamber. Thus, in this instance plastering of the top wall of the plenum chamber is likewise prevented, and the liquid material is properly distributed into the downflow tubes.

To briefly review operation of the complete apparatus shown in Fig. 1, the material to be concentrated, such as tomato pulp, is supplied by pump 64 to the preheater 62, after which the heated material is supplied to the upflow evaporating tubes of the first unit A. Material jetting from the upper ends of the upflow tubes of unit A is deflected downwardly within the plenum chamber 18, and re-enters the downflow evaporating tubes 12. A certain amount of vapor is continuously bled off from the upper portion of the plenum chamber 18, through the line 36.

Partially concentrated liquid material is removed from the first unit through line 42 and pump 61, and is delivered to the second unit B. The other liquid material is further concentrated by evaporation in the manner previously described, and the final concentrate removed through pipe 53. Vapor evolved in the two effects is utilized to heat the preheater 62, and in addition this preheater serves as a partial condenser for the two units.

I claim:

1. In an evaporating method for the concentration of liquid materials wherein liquid material to be evaporated is passed at high velocities through heated evaporating tubes, the improvement comprising causing the liquid material interspersed with evolved vapor to pass upwardly through one set of evaporating tubes, causing the liquid material and a substantial part of the vapor discharged from the first set of tubes to enter the second set of tubes, and diverting the remaining part of the vapor discharged from the first set of tubes.

2. In an evaporating method for the concentration of liquid materials wherein liquid material to be evaporated is passed at high velocities through heated evaporating tubes, the improvement comprising causing the liquid material interspersed with evolved vapor to pass upwardly through one set of evaporating tubes, separating a part of the vapor discharged from the first set of tubes from the mixture of liquid material and vapor, causing the mixture of liquid material and remaining vapor to be introduced into the second set of tubes, and removing the separated vapor.

3. In evaporating apparatus, two sets of generally upright evaporating tubes, the second set of tubes being grouped about the first set, means for introducing liquid material to be evaporated into the lower end of the first set of tubes, means for receiving evaporated material and evolved vapor from the lower end of the second set of tubes, a chamber serving to transfer evolved vapor and dispersed liquid from the upper end of the first set of tubes to the upper end of the second set of tubes, a deflecting nozzle disposed within the chamber and having its lower open end overlying the upper end of the first set of tubes, and a deflector overlying the upper open end of the nozzle and serving to deflect material down-

wardly and about the nozzle to the upper end of the second set of tubes.

4. In evaporating apparatus, two sets of generally upright evaporating tubes, means for introducing liquid material to be evaporated into the lower end of one set of tubes, means for receiving evaporated material and evolved vapor from the lower end of the second set of tubes, a chamber serving to transfer evolved vapor and dispersed liquid from the upper end of the first 10

set of tubes to the upper end of the second set of tubes, means in said chamber for deflecting liquid and vapor discharged from the upper end of the first set of tubes downwardly toward the upper end of the second set of tubes, and means for continuously bleeding from said chamber a portion of the vapor discharged from the first set of tubes.

DAVID D. PEEBLES.
